ROCKING TOY HORSE

Cecil Arthur Rassier, Erith, England

Application August 7, 1956, Serial No. 42,543

Term of patent 14 years

(Cl. D34—15)

FIG.1.

FIG.2.

FIG.3.

Fig. 1 is a top front perspective view of a rocking toy horse, showing my new design;

Fig. 2 is a bottom rear perspective view thereof; and
Fig. 3 is a top plan view thereof.

I claim:

The ornamental design for a rocking toy horse, as shown.
